UNITED STATES PATENT OFFICE.

WILLIAM R. ELIOT, OF MERIDEN, CONNECTICUT, ASSIGNOR TO THE INTERNATIONAL SILVER COMPANY, OF SAME PLACE.

DESIGN FOR A GLASS RECEPTACLE.

SPECIFICATION forming part of Design No. 32,211, dated February 13, 1900.

Application filed January 15, 1900. Serial No. 1,560. Term of patent 7 years.

To all whom it may concern:

Be it known that I, WILLIAM R. ELIOT, of Meriden, in the county of New Haven and State of Connecticut, have invented and produced a new Design for a Glass Receptacle, (Case B;) and I do hereby declare the following, when taken in connection with the accompanying drawings and the letters of reference marked thereon, to be a full, clear, and exact description of the same, and which said drawings constitute part of this specification, and represent, in—

Figure 1, a top or plan view of a receptacle embodying my design; Fig. 2, a sectional view of the same.

This invention relates to a design for a glass receptacle; and the design consists in the configuration and ornamentation as herein described, and shown in the accompanying illustrations.

As herein shown, in the bottom of the center is a many-pointed star A, having a hob B, and radiating from this central star and springing upward are feathers, each comprising a finely-lined body C and a hob star-tip D, ²⁵ having a punty E, giving them the semblance of peacock-feathers. Between the points of the feathers the surfaces or darts F are finely cut.

I claim—

The design for a glass receptacle substantially as shown and described.

In testimony whereof I have signed this specification in the presence of two subscribing witnesses.

WILLIAM R. ELIOT.

Witnesses:

HENRY J. MARTIN,
JAMES E. PRATT.
